UNITED STATES PATENT OFFICE.

MORRIS MOSKOWITZ, OF NEW YORK, N. Y., ASSIGNOR, BY MESNE ASSIGNMENTS, TO U. S. LIGHT & HEAT CORPORATION, OF NIAGARA FALLS, NEW YORK, A CORPORATION OF NEW YORK.

SYSTEM OF ELECTRIC REGULATION.

1,291,598.

Specification of Letters Patent. Patented Jan. 14, 1919.

Application filed March 25, 1909, Serial No. 485,707. Renewed May 27, 1918. Serial No. 236,926.

To all whom it may concern:

Be it known that I, MORRIS MOSKOWITZ, a citizen of the United States, and a resident of the borough of Manhattan, county of New York, city and State of New York, have invented certain new and useful Improvements in Systems of Electric Regulation, of which the following is a specification, accompanied by drawings.

10 This invention relates to a system of electrical regulation to be used more especially in connection with a constant current generator for car lighting from the axle. The invention may be used in any connection in which it is found applicable, however.

The object of the invention is to enable efficient regulation of a lamp circuit or other work circuit when supplied from a system in which there is a main source of supply, for example a generator, and an auxiliary source of supply, as for instance a storage battery connected in parallel therewith. Certain subject-matter disclosed but not claimed herein is claimed in an application of the 25 same applicant, Serial No. 497,725, filed May 22, 1909; forfeited and renewed as application No. 715,303.

Referring to the drawings:

A represents the armature of a variable speed generator whose field winding (not shown) may be regulated in any suitable manner to maintain substantially constant the current delivered to the external circuit across which the lamps B and storage battery C are connected in parallel branches. A variable resistance is connected in series between the storage battery and the lamps for regulating purposes. This resistance may assume any one of a number of forms. 40 The preferred form is that shown in the drawing in which the resistance is illustrated as a variable pressure rheostat comprising two sets of carbon blocks R preferably arranged horizontally with means located between the two sets for varying the pressure thereon to vary the resistance. The pressure exerted on the carbon blocks and hence the resistance thereof, is controlled by an electromagnetic device E comprising a series winding G connected in the battery branch of the external circuit, and a second series winding F connected in series with the lamps to respond to variations in current in the lamp circuit and connected

55 preferably between the resistance R and the point of juncture of the battery branch with one of the main leads of the external circuit.

50 The mechanical connections between the controlling windings F and G and the two sets of carbon blocks R comprise an arrangement of levers which form a toggle joint made up of the yoke O and the links P pivoted to said yoke. The rod J passes loosely through the yoke O and is preferably insulated therefrom by the insulating sleeve Q. Stops S and T on the rod J are adapted to engage the yoke and adapted to lift or depress the same in accordance with the movement of the rod, a slight looseness or 65 vertical play being permitted between the stops and the yoke, as shown. The upper end of the rod is provided with a compression spring D secured between a relatively fixed support V and an adjusting nut U on 70 the rod J, which spring normally tends to lift the rod and thereby release the pressure on the carbon blocks whereby the resistance 75 thereof is normally a maximum. The resistance of the sets of carbon blocks, however, may be decreased by the drawing down of the rod J through the energization of 80 either of the controlling windings F or G, or by the energization of both of said windings acting cumulatively. The electromagnetic device E is provided with a suitable frame H. The rod J, which extends through this frame, is provided with the movable core K. It also passes through the fixed core L of the auxiliary magnet.

85 An automatic switch W is provided for connecting the generator with the storage battery and lamps when the generator develops a voltage in excess of the battery voltage, and is thereby enabled to charge the 90 battery and carry the lamp load. The automatic switch opens and disconnects the generator from the external circuit when the generator is at rest or is rotating at such a low speed that the voltage thereof is lower 95 than the battery voltage. The automatic switch is also provided with auxiliary contacts for short circuiting the resistance R and the controlling winding F associated therewith, whenever the automatic switch is open, 100 at which time the lamp load is being carried by the battery alone. The switch comprises the lever a having an insulating block

105

5 to which is connected the contact *c* adapted to bridge the contacts *d* and *e* to close the external circuit of the generator. An additional contact *f* is provided and is adapted 10 to make contact with the lever *a*, which is connected through the conductor *g* to a point *h* between the lamps *E* and the resistance *R*.

10 The operation of the system will now be described:

15 When the generator is at rest or when its armature is rotating at a low speed, the lamp load, if any, is carried by a storage battery, the automatic switch being open. Under these conditions the controlling winding *F* is quiescent, being short circuited by the auxiliary contacts of the automatic switch. The resistance *R* is also short circuited. The lamps are supplied with battery current 20 which flows through the controlling winding *G*, the latter producing no regulating effect as the resistance *R* is short circuited.

Upon increased speed of rotation of the generator armature, due to an increase in 25 the train speed, for example, where the generator is driven from a car axle as in car lighting systems, the generator voltage increases with the speed until it is equal to or slightly in excess of the battery voltage.

30 The attainment of this predetermined voltage causes the closing of the automatic switch through certain means not shown on the drawing but well understood in the art. The generator now charges the storage battery and carries the lamp load. As the generator is being automatically regulated to furnish substantially constant current to the external circuit, the voltage of the system will vary in accordance with various factors,

35 one of which is the counter-electromotive force of the battery, which rises somewhat during the normal charging period and which rises considerably when the battery approaches a fully charged condition. The current supplied by the generator flows through the regulating winding *G* to the storage battery, and generator current also flows through the winding *F* to the lamp circuit. The coils *F* and *G* act 45 differentially under these circumstances, the coil *F* tending to decrease the resistance *R* and the coil *G* acting to offset the action of the coil *F*, and accordingly tending to increase said resistance. If the lamp load is a

50 maximum most of the current is consumed by the lamps and very little current flows to the storage battery through the coil *G*. As a result of the reduction in the amount of current supplied to the storage battery 55 there will be a certain reduction in generator voltage. The energization of the winding *G* at this time being very slight, and the winding *F* predominating, the resistance *R* will be decreased, thereby permitting 60 the desired maximum current to be sup-

plied to the lamps. As the lamps are turned off the proportion of the total current supplied to the storage battery, as compared to the proportion supplied to the lamps, will increase. This increase will be accompanied 70 by a tendency toward an increase of voltage at the generator terminals. The decrease in current demanded by the lamp circuit results in a weakening of the coil *F* and a consequent reduction in the pressure on 75 the carbon rheostats *R*. The increase in battery current strengthens the coil *G* which opposes the coil *F* and thereby still further reduces the effectiveness of the same. The resistance *R* is, accordingly, increased to 80 maintain an approximately constant voltage on the lamp circuit. The regulator, therefore, has a compounding effect on the lamp circuit and tends to maintain an approximately constant voltage on the lamps. 85

When the generator voltage is reduced below the battery voltage, due to a slowing down of the car for example there is a certain period prior to the opening of the automatic switch when the battery carries the 90 lamp load and also begins to discharge through the generator. The current now flows in the coil *G* in the reverse direction, causing the same to act cumulatively with the coil *F*, thereby decreasing the resistance 95 *R* in accordance with the requirements of the work circuit. After the automatic switch opens, the resistance *R* and the coil *F* are short circuited. Under these circumstances the regulator is inert and the battery supplies the work circuit.

The toggle mechanism for controlling the compressible rheostat possesses many advantages over the ordinary operating mechanism. These advantages are pointed out 105 and claimed in a copending application Serial No. 497,725, filed by me May 22, 1909.

Various changes may be made in the system described without departing from the spirit of the invention.

What I claim as new and desire to secure by Letters Patent of the United States is:

1. In a system of electric regulation, the combination of a main source of supply and work circuit, an auxiliary source of supply 115 connected in parallel with the main source of supply, a resistance in series with the work circuit, and an electro-responsive device for controlling said resistance, having coils connected in the system, one in series 120 relation to the work circuit and another in series relation to the auxiliary source and acting cumulatively when said auxiliary source is supplying current to the work circuit.

2. In a system of electric regulation, the combination of a main source of supply and work circuit, an auxiliary source of supply, a resistance in series with the work circuit, and an electro-responsive device for control- 125 130

ling said resistance, having two coils, one of which is connected in series between the work circuit and the main source so as to be responsive to the main source of supply and 5 the other connected in series with the auxiliary source.

3. In a system of electric regulation, the combination of a main source of supply and work circuit, an auxiliary source of supply 10 connected in parallel with the main source of supply, a carbon block resistance in series with the work circuit, and an electro-responsive device for controlling said resistance, having means for influencing it by the auxiliary source of supply and means for influencing it by the current supplied to the 15 work circuit.

4. In a system of electric regulation, the combination of a main source of supply and 20 work circuit, an auxiliary source of supply connected in parallel with the main source of supply, a carbon block resistance in series with the work circuit and an electro-responsive device for controlling said resistance, 25 having two coils, one of which is connected in series relation to the work circuit and the other in series relation to the auxiliary source and acting cumulatively when the auxiliary source is supplying current to the 30 work circuit.

5. In a system of electric regulation, the combination of a source of supply, a work circuit, a storage battery in parallel with the source of supply, a carbon block resistance in 35 series with the work circuit, a toggle acting lever adapted to exert pressure upon said carbon blocks, a spring connected to relieve the pressure on said blocks and a magnet opposing the spring, said magnet having 40 two coils, one of which is in series between the work circuit and the source of supply and the other of which is in series with the battery, whereby said coils act differentially or cumulatively according to the requirements 45 of the system.

6. In a system of electric regulation the combination of a main source of supply and work circuit, a battery connected in parallel with the main source of supply, a resistance 50 in series with the work circuit, an electro-responsive device for controlling the resistance having one coil in series between the work circuit and the source of supply and another coil in series in the battery circuit, 55 and a switch for short circuiting the said resistance.

7. In a system of electric regulation, the combination of a main source of supply and work circuit, a battery connected in parallel 60 with the main source of supply, a resistance in series with the work circuit, an electro-responsive device for controlling the resistance having one coil in series between the work circuit and the source of supply and 65 another coil in series in the battery circuit,

and a switch for short circuiting the said resistance and breaking the circuit of the main source of supply.

8. A car lighting system having a battery circuit and a lamp circuit, and a regulator 70 for the lamp circuit, said regulator having in combination, a plurality of current responsive coils arranged to act differentially or accumulatively, one of said coils connected in the battery branch of said system and 75 the other of said coils connected in the lamp circuit branch thereof.

9. In combination, a circuit to be regulated, a regulator in said circuit, a movable rod for operating said regulator, a coil having a core fixed to said rod and a second coil having a core slidable on said rod, whereby said first coil may operate said 80 regulator and said second coil may increase or decrease the effectiveness of said first coil 85 depending on the polarity of said second coil.

10. In combination, a circuit to be regulated, a storage battery connected across said circuit to be charged thereby or to 90 deliver current thereto, a variable resistance in said circuit, means including a movable member for varying said resistance, a coil connected in series in said circuit said coil having a core movable with said member and a second coil connected in series with said battery, said second coil having a core mechanically independent of said movable member whereby said second coil may 95 increase or decrease the effectiveness of said first coil, depending on whether said battery is delivering current to said circuit or is being charged thereby.

11. In a car lighting system, a generator, a storage battery, a lighting circuit, an 105 automatic switch for connecting said generator to said storage battery and said lighting circuit, a regulator for the lighting circuit, and, a shunt circuit around portions of the system including operating 110 means for said lighting circuit regulator, said automatic switch having means for completing said shunt circuit when the switch is open.

12. In a car lighting system, a source of 115 supply, a storage battery, a lighting circuit, an automatic switch for connecting said source to said battery and lights, a regulator for the lighting circuit, and means under control of said automatic switch for 120 short-circuiting said lighting regulator and its operating means when said automatic switch is open.

13. In a car lighting system, a main source of supply, a secondary source of supply, 125 a lamp circuit, an automatic switch between said main source and said secondary source of supply, a regulator for said lamp circuit, said regulator having an electro-magnetic operating coil and means under control of 130

said automatic switch for completing a shunt circuit around portions of said system including said operating coil.

14. In a car lighting system, a main source 5 of supply, a secondary source of supply, a lamp circuit, an automatic switch between said main source and said secondary source of supply, a regulator for said lamp circuit, said regulator having an electro-magnetic 10 operating coil, and means under control of said automatic switch for short-circuiting said regulator and its operating coil when said automatic switch opens.

15. In a car lighting system, a main source 15 of supply, a secondary source of supply, a lamp circuit, an automatic switch between said main source and said secondary source of supply, a variable regulator for said lamp circuit operating means therefor, and means 20 controlled by said automatic switch to render said lamp circuit regulator operating means ineffective when said automatic switch is open, said switch controlled means including a short-circuit adapted to be completed around portions of the system including said regulator operating means.

16. In a system of electrical regulation, a constant current source of supply, a storage battery to be charged thereby, a lamp circuit 25 and a regulator for said lamp circuit, said regulator including a variable resist-

ance in series in the lamp circuit, an operating coil in the lamp circuit tending to decrease said resistance in response to increases in current demands by said lamp 35 circuit, and an auxiliary coil for said regulator, said coil responding to current in the storage battery branch of the system and tending to oppose said first coil in proportion to current flowing to the battery. 40

17. In a system of electrical regulation, a constant current source of supply, a storage battery to be charged thereby, a lamp circuit and a regulator for said lamp circuit, said regulator including a variable resistance in series in the lamp circuit, an operating coil in the lamp circuit tending to decrease said resistance in response to increases in current demands by said lamp 45 circuit, and an auxiliary coil for said regulator, said coil responding to current in the storage battery branch of the system and tending to oppose or aid said first coil, depending on whether current is flowing into or out of said storage battery. 50

In testimony whereof I have signed this specification in the presence of two subscribing witnesses, March 24, 1909.

MORRIS MOSKOWITZ.
